UNITED STATES PATENT OFFICE.

ISAAC A. ELROD, OF FAUCETT, MISSOURI.

GRAIN-SHOCKER ATTACHMENT TO A BINDER.

1,188,258.

Specification of Letters Patent. Patented June 20, 1916.

Application filed February 25, 1914. Serial No. 820,863.

To all whom it may concern:

Be it known that I, ISAAC A. ELROD, a citizen of the United States, residing at Faucett, in the county of Buchanan and State of Missouri, have invented certain new and useful Improvements in Grain-Shocker Attachments to Binders; and I do hereby declare the following to be a full, clear, and exact description of the invention, such as will enable others skilled in the art to which it appertains to make and use the same.

This invention relates to attachments for binders and has for its primary object to provide a shocker attachment for connection with binders, and which will be simple in construction and operation as well as highly efficient in use.

Another object is to provide an attachment of this character including a shock former connected with a supporting platform and adapted to rest in normal position to receive the sheaves forming the shocks, then to be swung to position to support the shocks during the operation of capping the same, and finally released to permit the shock former to deliver the shocks from the machine.

A further object is to provide a device of this character in which the mechanism for supporting the shock former in its various positions will be mounted upon the platform and will be of such construction and operation that the shock former will be supported securely in position to hold the shock in a substantially upright position during the operation of capping the shocks.

A still further object is to construct the device in such manner that it will simply be necessary to press a lever to release the shock former from its locked position when the operation of capping the shock is completed, to allow the shock former and shock to swing downwardly and thereby discharge the capped shock.

A still further object is to generally improve and simplify the construction and operation of devices of this character and increase the efficiency thereof without materially increasing the cost of the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a side elevation view of my shocker attachment, Fig. 2 is a longitudinal sectional view thereof, Fig. 3 is a top plan view of the same, Fig. 4 is a detail sectional view on the plane of line 4—4 of Fig. 3, and Fig. 5 is a detail sectional view taken on the plane of line 5—5 of Fig. 4.

Referring more particularly to the drawings in which similar reference characters designate the corresponding parts throughout the several views, 1 designates the platform which has the upstanding flanges 2 and which is mounted upon suitable wheels 3. The wheels are mounted in the transverse beams 4 secured beneath the platform 1 and by means of which the device may be secured to a binder.

To the rear end of the platform 1, I have pivoted the base 5 of the shock former 6, the body portion of which is of substantially semi-circular form and extends upwardly from the base 5. When the shock former 6 is in position to receive the sheaves from the binder to form a shock, the body of said shock former is tilted forwardly and rests upon the upper diverging ends 7 of the supports 8 which have their lower ends turned outwardly and secured upon the platform 1, as shown at 9. The supports 8 are connected intermediate their ends by the cross connecting bar 10 which has a guide slot 11 in its upper edge, the purpose of which will presently appear.

After the desired number of sheaves have been placed in the shock former 6 by the attendant, to form the shock, the shock former is swung to the position shown in Fig. 1 by grasping the front or handle end 12 of the slide lever 13 and forcing said lever rearwardly, the rear end of said lever being detachably connected with the ear 14 on the under face of the body of the shock former. It will also be seen that the slide lever 13 is slidably mounted in the guide slot 11 of the connecting cross bar 10 and has a substantially V-shaped notch 15 in its lower face, whereby said lever may be locked against further rearward movement after forcing the shock former to proper position. The slide lever 13 is resiliently retained against upward movement and thereby prevented from disengagement with the slot 11, by

means of the helical spring 16 and the latch plate 17, said spring 16 having one end secured to the platform 1, while its opposite end is secured to the lower edge of the latch plate 17, which latter has a longitudinally elongated slot 18 to accommodate the slide lever 13, with a roller 19 in the upper end of said slot and engaged upon the upper edge of said slide lever 13 to reduce friction to the minimum. The latch plate 17 is retained in proper engagement with the connecting cross bar 10, by means of the depending arm 20 formed on the said latch plate 17 and engaged against the rear face of said connecting cross bar 10, while the remainder of said latch plate 17 is positioned forwardly of said connecting cross bar 10.

The shock within the shock former 6 may be compressed in any suitable manner by any preferred means for the purpose of capping the shocks and for this purpose I have provided an adjustable strap 21, the length of which may be readily regulated by means of the buckle 22 upon one end of the strap 25 and the series of openings 23 along said strap. Within the loop end 24 of the strap 21 is a link 25 adapted for engagement over the supporting lug 26 projecting from one longitudinal edge of the body of the shock former 6 when the shock tightener is in use, the strap 21 passing around the shock former and being passed between the spaced guide lugs 27 of the plate 28 secured to the other side of the shock former, said guide lugs 27 also projecting beyond the edge of the shock former. Secured upon the remaining end of the strap 21 is a lever 29 which has the longitudinally extending hook 30 for engagement with the link 25, and a transverse hook 31 for engagement with the strap 21 adjacent the end secured to the lever 29, thereby compressing the shock and retaining the same in compressed form during the operation of capping said shock.

After the capping operation is completed, it is simply necessary to press downwardly the free rear end of the releasing lever 32 and swing the lever upon its pivot 33 in the bracket 34 secured to the upstanding flange 50 2 of the platform, the opposite end of said lever 32 being connected with the upper end of the helical spring 16 and the lower end of the latch plate 17, whereby upon downward movement of the rear end of the lever and 55 upward movement of the forward end thereof, the latch plate 17 will be forced upwardly, thereby allowing the shock former 6 and the shock therein to swing downwardly, owing to the combined weight of 60 said shock former and shock, thereby delivering or discharging the shock from the shock former, it being clearly understood that the shock tightening means is removed

immediately after the completion of the capping operation. In practical use of the shocker it may be necessary, for two operators to conveniently operate the same, one to operate the lever 13 and the other to operate the lever 29. As soon as the shock is discharged from the shock former, the latter is automatically returned to normal position by means of the spring 35 which has one end connected with the shock former 6, while its opposite end is connected with one of the flanges 2 of the platform 1. If desired, a rod 36 may be secured to the foremost transverse beam 4 to connect the device with the tongue or other suitable portion of the binder. It will be understood that, as the binder forms no part of this invention, it is not shown in the drawing. In order to securely brace the support 8, I have provided an inclined brace member 37, which has one end secured to the platform 1 while its opposite end is secured to one of the supports 8, as will be readily understood.

While I have shown and described the preferred embodiment of my invention, it will be understood that minor changes in construction, combination and arrangement of parts may be made without departing from the spirit and scope of the invention as claimed.

Having thus described my invention, I claim:—

A device of the character described comprising a platform, a shock former hinged to said platform, outwardly flared supports for said shock former to limit forward tilting movement thereof, said supports being secured to the platform forwardly of the shock former, a bracing member for said supports, a lever carried by said shock former, said lever having a notch formed in its under edge for engaging said bracing member for locking the lever against movement, a latch plate mounted over said lever and said bracing member, a spring connected to said latch member to prevent upward movement of the latch member and said lever, means for releasing said lever to permit the same to move across said bracing member, means carried by the shock former for compressing a shock within the same for the purpose of capping said shock, said shock former being adapted to swing rearwardly and discharge the shock when the lever is released, and means for returning the shock former to normal position.

In testimony whereof I affix my signature in presence of two witnesses.

ISAAC A. ELROD.
